UNITED STATES PATENT OFFICE

2,507,990

METHOD FOR AMPLIFYING SMALL MOVEMENTS AND APPARATUS FOR THE APPLICATION THEREOF

Georges Minot, Ezanville, France

Application June 28, 1946, Serial No. 679,963
In France January 17, 1945Section 1, Public Law 690, August 8, 1946
Patent expires January 17, 1965

4 Claims. (Cl. 250—233)

1

My invention has for its object to provide a method for amplifying small movements by means of a photo-cell recording the variations in luminosity of a radiologic screen on which is shown the shadow of the body executing the small movements and exposed to X rays.

Another object of my invention is to provide an apparatus for amplifying small movements of a body irradiated by X rays, said apparatus comprising an X-ray source, the X-ray beam of which impinging upon a radiologic screen on which appears the shadow of the body placed between the X-ray source and said screen at the back of which is a photo-cell connected to an amplifier controlling a measuring instrument.

The rays which light the photo-cell are advantageously pulsatory so that it is possible to use an amplifier for alternating current, said amplifier being preferably tuned to the frequency of the pulsatory rays impinging upon the photo-cell.

It should be noticed lastly that the arrangement forming the object of the invention is not necessarily limited to the recording of very small movements; it may also serve for movements of a certain amplitude.

Other features and advantages of my invention will appear moreover in the reading of the following description with reference to accompanying drawings given out solely by way of example and wherein:

Fig. 1 is a diagrammatic showing of an arrangement according to my invention.

Fig. 2 is a part of a form of execution corresponding to Fig. 1 for application thereof to the study of the movements of the veins.

Fig. 3 shows diagrammatically a modification of the system with a stationary screen.

Fig. 4 illustrates in a diagrammatical perspective view the chief elements of another form of execution.

Lastly Fig. 5 is a partial view of an arrangement for the occultation of the beam.

In these different figures, the same reference numbers designate similar parts.

In the form of execution illustrated in Fig. 1, the apparatus comprises a source of light 1, preferably linear, constituted by a filament perpendicular to the plane of the figure. A condenser 2 produces a light beam 3 defined by the diaphragm 4 and falling on a cylindrical lens 5 the axis of which is perpendicular to the plane of the figure.

This lens 5 forms a luminous beam including a thin flat zone perpendicular to the plane of

2

the figure. In front of said zone lies a screen 8 the outer edge of which 9 is true in a plane perpendicular to the plane of the figure so that the screen 8 may cut off a more or less considerable part of the beam in the above mentioned thin zone. The remainder of the beam impinges on the photo-cell 10.

This cell 10 cooperates with a direct current voltage amplifier which is illustrated as constituted by an electronic multiplier 12. The cathode of the photo-cell is grounded and its anode connected to the positive pole of a high tension source through a resistance 13, the two ends of which are connected respectively with the grid 14 and the cathode 15 of the amplifier tube 12. The screening grid 16 and the secondary cathode 17 of this amplifier tube 12 are also connected with the positive poles of high voltage sources while the anode 18 is connected through a lead 19, also connected through a resistance 20 to a source of high voltage, and through a condenser 21 to an electrostatic oscillograph 22 for recording or for visual supervision, such as a quartz oscillograph. The mounting would be slightly modified in the case of a magnetic oscillograph.

One of the two elements, cylindrical lens 5 or screen 8, is stationary while the other element is connected with the body of which it is desired to study the movements and which may be constituted by the moving member of an electrometer, electroscope or the like so that said element may assume a translational or a rotational movement perpendicularly to the beam 3 under the control of said movements. This produces thus a more or less considerable occultation of the beam 3 by the screen 8, which leads to corresponding variations in the current flowing through the photo-cell 10, which variations are transformed and recorded by the oscillograph 22. The latter may as well make said variations appear under the form of curves on a fluorescent or the like screen.

A milliammeter 24 is inserted in the circuit of the amplifier 12 and allows an adjustment of the system as obtained by adjusting the relative positions of the screen 8 and of the beam 3, whereby the mean intensity given out may be that which corresponds to the proper operation of said amplifier.

Fig. 2 illustrates a form of execution adapted more particularly for use for physiological purposes, for instance for the examination through contact of the movements of the veins, said form of execution including a casing 25 enclosing the

source 1 and the cell 10. One wall 26 of this casing is elastic and carries the screen 8 of which an extension 28 beyond the casing may be set in contact with the vein or the like part of which it is desired to study the movements. Such an apparatus exerts obviously only a very small pressure on the vein the movements of which are transmitted with a high accuracy.

Fig. 3 shows a further form of execution according to which the source 1 cooperates with a mirror 29 reflecting into the direction of a photo-cell 10 a beam 3 more or less cut off by the screen 8. Said screen 8 is stationary and the mirror 29 is pivotally secured to a pivot 31 round which it rotates under the control of the movement to be examined and which is transmitted to it for instance through a rod 30.

Obviously as in the above example the occultation of the beam and consequently the current flowing through the cell 10 depend on said movement.

In Fig. 4, 1 designates the source emitting radiations constituted in the present case by a source of X rays fed with direct current cut off at a frequency F and emitting a beam 3; the frequency F is preferably all the higher when the movement is more rapid. Behind an ordinary radiologic screen 32 is arranged a photo-cell 10, the entrance gate into which 33 has an elongated rectangular cross-section and is arranged in a manner such that the small side of said cross-section may be substantially perpendicular to the direction of the movements under examination. This photo-cell 10 is inserted in a system comprising an amplifier 46 and a recorder 41 of a known type. The amplifier is executed for operation at a mean frequency F.

It has been supposed that the above arrangement is used for the examination of the beats of a human heart 34. The beam 3 projects on the radiologic screen 32 a shadow 35 the edge of which passes through the rectangular surface 36 of the screen lying in front of the gate 33 of the photo-cell. This surface 36 is thus more or less invaded by the shadow 35 and the consequent variation in luminosity has an action on the photo-cell 10. The variable electric current generated by the cell is then amplified and used as precedingly for amplifying any desired indicating or recording apparatuses.

The modification of a part of the arrangement illustrated in Fig. 5 differs from the preceding arrangement only through the use of a continuous emitting supply of radiations 1a in front of which are located occulting means constituted by a disc 37 of a material opaque with reference to the radiation used, lead for instance for X rays and provided with gates or slots 38 or with any other means for modifying its opacity at different points of the disc. Said disc is caused to rotate for instance through the agency of a small motor 39 at a speed such that F slits 38 may pass in front of the source 1a during unit time. The beam used assumes thus a pulsatory character at a frequency F as in the preceding case.

Obviously, my invention is by no means limited to the details of execution illustrated or described which have been given out solely by way of example. It is also possible to insert an optic system between the radiologic screen and the photo-cell in order to concentrate on the radiation sensitive part of the latter the light from the screen surface which is to be examined.

What I claim is:

- 10 1. An arrangement for amplifying small movements, comprising a photo-cell, an amplifier connected with the output of said cell, means controlled by the amplifier for allowing examination of the movements considered, a radiologic screen arranged before said cell, an X-ray source for directing an X-ray beam on said radiologic screen, means for making pulsatory the rays coming from said screen and impinging upon the photo-cell, means for positioning, in the X-ray beam, a body executing the small movements to be studied the shadow of which appears on said radiologic screen and a diaphragm disposed between the X-ray source and the photo-cell for defining a screen zone wherein is at least one portion of the shadow outline of the body executing the small movements.
- 20 2. An arrangement for amplifying small movements as claimed in claim 1, wherein said diaphragm is substantially rectangular and positioned between the radiologic screen and the photo-cell.
- 25 3. An arrangement for amplifying small movements as claimed in claim 1, wherein the means for making pulsatory the rays which impinge upon the photo-cell are constituted by periodic occulting means inserted between the X-ray source and the photo-cell.
- 30 4. An arrangement for amplifying small movements as claimed in claim 1, wherein the means for making pulsatory the rays which impinge upon the photo-cell are constituted by a rotating opaque disc disposed on the path of the X-ray beam and having peripheric disposed zones which are permeable to the X rays.
- 35 5. GEORGES MINOT.
